UNITED STATES PATENT OFFICE.

EDGAR S. YERGASON, OF HARTFORD, CONNECTICUT.

DESIGN FOR A CURTAIN AND LOOP.

SPECIFICATION forming part of Design No. 11,947, dated August 17, 1880.

Application filed May 28, 1880. Term of patent 14 years.

To all whom it may concern:

Be it known that I, EDGAR S. YERGASON, a citizen of the United States, residing at Hartford, in the county of Hartford and State of Connecticut, have invented and produced a new and original Design for a Curtain and Loop, of which the following is a specification, reference being had to the accompanying photographic illustration, forming a part thereof.

10 Heretofore curtains have been looped back at the sides by means of cords or braids, ornamental or otherwise, which have been attached to the sides or casing of the window or door and passed around the folds of the material. These 15 loops have been made of silk or woolen, or of an inferior material covered with silk or woolen, and have been of a perishable nature, soon becoming frayed and moth-eaten.

The leading feature of my design consists 20 in looping back a curtain by means of an ornamental chain in the place of the customary cord.

The curtain is of that class which is gathered to one side and looped.

25 The chain consists of a series of links with a ring at each end, which rings are passed over an ornamental hook attached to the side of the casing of the window or door to which the curtains are applied. One end of the chain

can be permanently united to the hook if desired, as it is only necessary to unhook one end to loop or unloop the curtains.

In the accompanying illustration, A is the chain. B is the hook. C is the curtain to which they are applied.

35 My invention is especially adapted to curtains made of heavy, rich, and ornamental silk or woolen goods, and particularly to those which are hung upon metallic bars or supports at the top, the whole presenting a superior symmetry and finish much more elegant than when the curtains are looped back by cords in the customary manner.

40 The chains can be made of a variety of ornamental forms and with a high degree of finish, and will retain their beauty for an almost unlimited period of time.

45 What I claim to have invented and produced is—

A new and original design for a curtain and loop, consisting of an ornamental metallic chain, in connection with a curtain adapted to be gathered to the side of the window and be held by said chain, substantially as described.

EDGAR S. YERGASON.
